DESIGN FOR A PORTABLE PRESS

James S. Rodgers, Minneapolis, Minn., assignor
to Rodgers Hydraulic Incorporated, Minneapolis, Minn., a corporation of Minnesota

Application March 10, 1938, Serial No. 75,719

Term of patent 14 years

To all whom it may concern:

Be it known that I, James S. Rodgers, a citizen of the United States, residing at Minneapolis, in the county of Hennepin and State of Minnesota, have invented a new, original, and ornamental Design for Portable Presses, of which the following is a specification, reference being had to the accompanying drawing, forming part thereof, and in which

Figure 1 is a side elevational view of a portable press showing my new design;

Figure 2 is a top view thereof; and
Figure 3 is a sectional plan view on the line
3—3 of Figure 1.

The dominant features of my design reside in the portions shown in full lines.

I claim:

The ornamental design for a portable press, as shown and described.

JAMES S. RODGERS.
